APPARATUS FOR CLEANING EQUIPMENT
WITH A CHEMICAL AGENT

Pasquale Greco, New York, N. Y.

Application September 10, 1945, Serial No. 615,489

1 Claim. (Cl. 34—104)

(Granted under the act of March 3, 1883, as
amended April 30, 1928; 370 O. G. 757)**1**

This invention relates in general to apparatus for cleaning industrial equipment and in particular to apparatus for flushing and cleaning industrial equipment used in connection with oil and oily materials.

A method now in use for cleaning equipment such as fuel oil heaters, storage tanks, and other equipment used in connection with oil or oily substances involves using a chemical cleaning agent in conjunction with a system of tanks and pipes that comprises a pair of tanks each containing a heating coil placed below the equipment to be cleaned and connected thereto to operate in the following manner. A cleaning chemical such as carbon tetra-chloreethylene is charged into one of the tanks, heated to vaporization temperature and the vapor passed into the oily equipment. The vapor cleans the equipment, condenses, and drains back into the other tank. Subsequently the second, or receiving tank, is heated and the vapor passed through the equipment in the reverse direction.

When this cleaning method is applied to equipment on board ship and in other confined places it is necessary to disassemble the cleaning apparatus in order to take it to a place below the equipment to be cleaned, such as the fire room below decks, and reassemble it there. In addition this gives rise to industrial hazards because of exposure to frequent contact with the chemical agent and because of the tendency to create leaks and other flaws in the apparatus by the continual assembling operations.

It is an object of this invention to provide a new and convenient apparatus for flushing and cleaning industrial equipment used with oil or oily substances, wherein the cleaning apparatus is located in an accessible place remote from the equipment to be cleaned.

It is an additional object to provide apparatus for cleaning and flushing equipment on board ship.

Further objects and advantages of this invention as well as the construction, arrangement and operation of the cleaning apparatus are apparent from the following description and claim in connection with the accompanying drawing, in which the single figure is a diagrammatic flow sheet showing the location and operation of the cleaning apparatus according to the present invention.

Referring to the figure in detail there is shown a fuel oil heater 11 to be cleaned with the cleaning apparatus of the present invention attached thereto. The fuel oil heater 11 is lo-

cated at a point below the deck line 12 of a ship, usually in the fire room. Above the deck line is a system of tanks and pipes as described above and including a pair of tanks 13 each provided with an inlet 14 for the chemical agent, an inlet 15 for the admission of steam, a vent line 16 and a steam drain 17. A pipe 18 leads from this unit below the deck line 12 to the fuel oil heater 11 and flows through this pipe 18 is controlled by valve 25. At a position below fuel oil heater 11 there is provided a receiving coil 20 connected to the fuel oil heater by means of a pipe 21 and valve 26. The receiving coil 20 is in turn connected back to tanks 13 by means of a pipe 22, and valve 27.

Leading into pipe 21 is an inlet 23 connected to a source of compressed air (not shown), the entrance of the compressed air being controlled by valve 28.

20 In the use and operation of this new cleaning apparatus the tanks 13 are set up in an accessible place above the deck line 12 preferably in the open air and connected to the fuel oil heater and receiving coil. Tanks 13 are charged according to conventional methods with a suitable mixture of the cleaning chemicals and steam, and the heated cleaning agent is then passed through the fuel oil heater 11 to the receiving coil 20. When a sufficient quantity of the cleaning agent has been passed through the fuel oil heater 11, valve 26 and optionally valve 25 are closed, valve 27 is opened and compressed air is admitted through inlet 23 to force the used cleaning agent back to tanks 13.

This cleaning process can be repeated until the fuel oil heater is satisfactorily cleaned.

By means of this invention it is now possible to use the described type of cleaning and flushing apparatus to clean fuel oil heaters, storage tanks, and the like aboard ship without necessitating constant assembling and disassembling of the equipment, and without exposing the operators to the danger of fumes or spatterings from the cleaning solution. The equipment is convenient to use and operate and permits carrying out the cleaning operations in a fraction of the time previously required for setting up the apparatus. In addition, there is eliminated the use of special hoisting equipment and the like that previously was necessary for setting the cleaning unit in a position below the equipment to be cleaned.

This invention has been particularly described in connection with the use of a pair of tanks 13 for cleaning a fuel oil heater. There can be

used any cleaning unit that operates by flushing the equipment with a flowable cleaning material. The cleaning apparatus is adapted to be used for cleaning any equipment located in a confined or inconvenient place and is not limited to the specific apparatus described in the specification and drawing.

It is to be understood that various modifications and changes may be made in this invention without departing from the spirit and scope thereof as set forth in the appended claim.

The invention described herein may be manufactured and used by or for the Government of the United States of America for governmental purposes without the payment of any royalties thereon or therefor.

What is claimed is:

A cleaning system for use on board ship comprising a tank for a chemical agent heating means for said tank to vaporize said agent, a first descending pipe between said tank and the object to be cleaned, a second descending pipe be-

5 tween the object to be cleaned and a receiving coil, a compressed air line connected to said second pipe, a third ascending pipe between said receiving coil and said tank, a valve in said first pipe, a valve in said second pipe between the object to be cleaned and said compressed air line, a valve in said compressed air line, and a valve in said third pipe.

10 PASQUALE GRECO.
